(57) **CLAIM**

I claim the ornamental design for a trade show booth, as shown and described.

DESCRIPTION

FIG. 1 is a perspective view illustrating my new design;

FIG. 2 is a top view thereof;

FIG. 3 is a bottom view thereof;

FIG. 4 is a side view thereof; and,

FIG. 5 is another side view depicting an entrance thereof.

The small circles on the top portion of the trade show booth depict lights.
